[57] ABSTRACT

Storage system for oil in impervious membrane envelopes comprising a water basin with communicating compartments each for one container, the system being such that optimal fire protection is achieved with minimal dimensions.

IMPERVIOUS MEMBRANE OIL STORAGE SYSTEM

The invention relates to a storage system for a fluid with a specific gravity lower than 1, for example crude oil, in which the fluid, confined in a container manufactured with the use of flexible material, floats on water.

Such a storage system is described in British Pat. No. 878,158. If in such a storage system the shell surrounding the oil goes out of order, any leakage oil will spread over a large surface area, which from the standpoint of fire protection, is very dangerous. In the conventional system use is, moreover, made of mooring cables, so that a large space must be available for the storage.

The object of the invention is to improve a storage system of the type described in which the protection against fire hazard is maximal and the utilization of space optimal.

According to the invention, the storage system is to this end characterized by means for restricting the contact surface with the outside air of oil flowing out in case of container fracture.

According to the invention, use is made of a basin in which, by means of partitions, a plurality of intercommunicating compartments are formed via a passage located adjacent the basin bottom, each being adapted to receive a flexible container.

In case of storage variation in one or more of the flexible containers in the basin, water can flow into or out of the compartment via the passages located adjacent the basin bottom, the arrangement being such that the level in all the compartments of the basin remains equal. Therefore, the partitions need not have a specific height above the water level.

These partitions have in addition a function which can best be compared with the well-known embankments around above-ground storage tanks. If a flexible container goes out of order, the oil only flows out over the surface of the respective compartment.

To prevent that outflowing oil from one specific compartment reaches one or more other compartments via the communication passage, the compartments according to the invention may each communicate with an equalizing duct and the latter via an overflow drain which is located on such a level that in case of container fracture the light layer of fluid formed in the compartment and floating on water is located above the drain opening, so that only water displaced by the fluid can escape through the drain.

So as to minimize the surface over which leaking oil in a compartment spreads and to also optimally use the space available for the storage, the horizontal peripheral configuration of each compartment according to the invention may correspond substantially to that of a filled, flexible container freely floating therein.

To prevent a fire formed in one compartment from spreading to other compartments, according to the invention the top edges of the partitions between the compartments may be provided with upwardly extending fire screens.

When oil in a specific compartment has flown out of the flexible container and, in the compartment, forms a layer which floats on water, the top surface of the oil layer will be on a higher level as a result of the lower specific weight than the water in the adjacent compartments. The result of this is that the partitions are subjected to a static pressure. This load is partly dis-

charged to the bottom via the partition and for the remaining part can be transmitted, according to the invention, via cables or chains attached to the respective upper ledges to other partitions. In view of this, the structure of each partition can remain relatively light in weight.

In order to impart to the side of the container which is exposed to the outer air a flat and therefore less vulnerable shape, a weighting layer may be mounted on 10 the flexible container according to the invention.

According to the invention a chain netting may also be suspended from the upper ledges of two partitions defining a reservoir, supplementary to or in lieu of the weighting layer and in lieu of the cables.

According to the invention, use can further be made in the storage device of containers each in the form of a closed envelope having a storage capacity which is at most equal to the volume of the compartment portion located above the communication opening in the partition. According to the invention, the envelope may be rectangular in an empty state. For optimal space utilization the envelope may have the same length and width in an empty condition as the compartment.

Additionally in connection with fire protection, in 25 each compartment at least the container may be covered by a layer of fireproof material. Moreover, the bottom side of the closed envelope may also be provided with a layer having insulating properties.

The envelope, which in an empty state is rectangular, will in the filled condition be elongated with a cross-section which is more or less in the shape of an ellipse. Although there is no objection to the filled envelope resting with its bottom surface on the bottom, according to the invention each envelope is preferably supported along the bottom surface by a layer of floating material, for instance a cork mat, so that the envelope will also float in an empty state.

In order to explain the invention, an exemplary embodiment of the storage system will be described with 40 reference to the drawing.

FIG. 1 is a top view of a basin for a plurality of flexible containers;

FIG. 2 is a sectional view on the line II-II in FIG. 1; FIG. 3 is a sectional view on the line III-III in FIG. 45 1;

FIG. 4 shows a sectional view of an oil-filled container floating on water and

FIG. 5 shows a graphic approach for the cross-sectional configuration of a filled container.

In the drawing, in particular FIG. 1, a rectangular basin 1, whose dimensions may be in practice 450 × 100 m, measured along the edge by an edge line 2 having a slope of 1 : 3. The slope of the line 2 is defined on the outer side by a basin edge 3 and on the inner side by a marginal baffle 4. The basin is divided by a plurality of partitions 5 into a number of compartments 6. The partitions 5 extend, just as the marginal baffles 4, into the bottom 7 of the reservoir. In the marginal baffle 4 located along the longer side of the reservoir there is provided, in each compartment, an overflow drain 8, whose inlet on the compartment side is adjacent the basin bottom 7.

FIG. 3 shows in cross-section a compartment 6 having therein an envelope 9 manufactured of flexible material, for instance impregnated nylon fabric. The envelope which is filled, for example with crude oil, floats in the water in the compartment, with a part of the

filled envelope extending above the water. The horizontal peripheral configuration of the filled envelope substantially corresponds with the rectangular shape of the compartment 6.

On the basis of an envelope length of 390 m, a storage capacity may be attained of about 450,000 m³.

If the dimensions of the compartment in which the filled envelope floats are $100 \times 390 = 390,00 \text{ m}^2$, 450,000 m³ oil will flow out over this surface if the envelope goes out of order. This oil then forms an oil layer (which remains covered by the envelope which has meanwhile been emptied) having a thickness of 11.54 m, of which 1.73 m remains above the water-line. At the water level there is therefore exerted a static pressure of 1.47 ton/m² on the partitions. The total pressure is 8.48 ton per meter of wall. This load is partly discharged via the wall to the bottom and the other part of the load via the upper ledge and a chain netting 11 to the opposite partition. In view of this chain netting, which also serves to maintain the envelope in position, the construction of the partition can remain relatively light.

The inlet of the overflow drain 8 on the side of the compartment must be so far down below the water level that no oil of the layer floating in the reservoir can escape via the drain to the equalizing duct 12. The equalizing duct 12 is located between the marginal baffle 4 and the basin edge 3 along one or both longer sides of the basin.

The total storage capacity of the entire basin would, in case of nine compartments, be $9 \times 450,000 \text{ m}^3 = 4 \times 10^6 \text{ m}^3$. Suppose that in practice the total storage variation is restricted to 10 percent thereof, in effect 400,000 m³, the variation in water level would be consequently be limited to less than one meter. Discharge or intake of water in the basin will therefore frequently not be necessary although there must be considered a possibility of this contingency arising.

FIG. 4 shows a section of an envelope 9 which is filled with oil and floating on water. In an empty state the envelope is rectangular and manufactured preferably of impregnated nylon fabric. Also applicable is the material of which the Dunlop dracones are made, or the NRDC made by Gordon Low. In an empty state lying on the water, the envelope rests on a layer of floating material 13 (for instance cork mats), while the top side thereof is covered with a layer of heavier material. Both the top side and the bottom side may have insulating properties, while the top layer may also be fireproof.

If the envelope is pumped full of oil, its cross-section will take the shape as shown in FIG. 4. The specific cross-sectional shape of the filled envelope and the fact that part thereof extends above water are the result of the fact that oil floating on water tends to spread over the largest possible surface and that each displaced m³ of water is capable of supporting one ton of oil, respectively.

At points A and B the pressure difference between the inner space of the envelope and the outer side is substantially nil and the curve of the envelope wall is 0. At the water-line the curve is maximal, because at this level the difference in static pressure of water and oil is highest. The static pressure of the oil varies according to the straight line A - D and the compensating water pressure according to the straight line C - D.

In case of a height A - C of from 2 to 2.5 m a maximum static pressure of about 2 tons/m² is attained. Taking this value as a starting point the envelope reservoir is therefore full if at the water-line a static pressure of 2 tons/m² prevails in the interior of the envelope. For different specific weights of oil the following values for A - C, A - B and C - D have been found:

	A - C	A - B	C - D
10 Specific weight = 0.8 - 3	2.50	12.5	10 m
Specific weight = 0.85 - 3	2.35	15.69	13.34 m
Specific weight = 0.9 - 3	2.22	22.22	20 m

It appears from the table that the envelope has a greater storage capacity as the oil becomes heavier.

As it is permissible that the envelope rest with the bottom surface thereof on the bottom in the middle of the compartment, the depth of the basin may be maintained, for instance, at 15 m.

FIG. 5 graphically shows in which manner the capacity of an envelope with a periphery of 200 m, (empty with a width of 100 m) can be reached. Since the capacity is dependent upon the specific weight, a calculation will be made, by way of example, for an oil filling having a specific weight of 0.85. In FIG. 5 the distance A - C = 2,35 m and the distance A - B = 15.69 m. The actual cross-sectional shape of the envelope ranges between two extremes, namely a rectangular section PQRS, whose width P - Q = 84.31 m, and a lozenge-like cross-sectional shape, ALBK, whose width K - L = 98.16 m. In both cases the periphery is equal to 200 m.

The surface area of the rectangle is 1323 m² and that of the lozenge figure 770 m². The shape of the envelope approaches, as regards surface area, the rectangular figure more closely than the lozenge figure and a section of 1200 m² is plausible. Per meter of length the envelope may therefore contain 1200 m³ oil.

It is clear that the invention is not limited to the above embodiment, but that variants are possible within the framework of the invention. For example, instead of a closed flexible envelope a domeshaped container of flexible material with open lower side may be used, whose horizontal dimensions correspond to those of a compartment.

I claim:

1. A device for storing a fluid with a specific gravity lower than 1, for instance crude oil, comprising a container of flexible material containing said oil, a receptacle laterally encompassing said container and having a substantially corresponding circumferential shape as the container, a quantity of water being provided in said receptacle for floatingly supporting said fluid-containing container thereon, said receptacle forming a water basin; partition means dividing said basin into a plurality of passages having communicating compartments located adjacent the bottom of the basin, each said compartment being adapted to accommodate one said flexible container.

2. A device according to claim 1, comprising equalizing duct means communicating each of said compartments, said duct means including an overflow drain on a predetermined level, whereby in case of container fracture, the light specific gravity fluid layer formed in the compartment and floating on water is located above the drain opening, so that only water displaced by the fluid can escape through the drain.

3. A device according to claim 1, comprising a plurality of said flexible containers in juxtaposed relation, said container being rectangular in configuration when empty, each said compartment being correspondingly rectangular and having the same peripheral dimensions as the containers.

4. A device according to claim 1, comprising upright fire screen means being positioned along the top edges of the partition means intermediate the compartments.

5. A device according to claim 3, comprising guy ropes connecting the upper ledges of each partition means to other of said partition means.

6. A device according to claim 3, comprising chains connecting the upper ledges of each partition means to other of said partition means.

7. A device according to claim 3, comprising chain netting being suspended from the upper ledges of two partition means defining a compartment.

8. A device according to claim 3, comprising a layer of fire-resistant material covering at least the container in each said compartment means.

9. A device according to claim 3, comprising an insulating layer being provided on the bottom of each said flexible container.

10. A device according to claim 3, comprising a layer of floating material being positioned below each said flexible container so as to support the bottom thereof, said layer being constituted of at least one cork mat.
